Primary Examiner—Robert M. Spear

(74) Attorney, Agent, or Firm—Varnum, Riddering,
Schmidt & Howlett LLP(57) **CLAIM**

I claim, the ornamental design for single-sided power and data center, as shown and described.

DESCRIPTION

FIG. 1 is a perspective view of a single-sided power and data center according to my design, and showing a cover of my design in a closed position;

FIG. 2 is a top plan view thereof;

FIG. 3 is a left side elevational view of the first embodiment of my design, with the cover shown in an open position;

FIG. 4 is a front elevational view of my design, with the cover shown in an open position as in FIG. 3; and,

FIG. 5 is a perspective view of my design in the same orientation as in FIG. 1, but with the cover in an open position as shown in FIGS. 3 and 4.

The broken lines in the drawings depict environmental structure, which forms no part of the claimed design.
